see sheet 1, drawing 1, of drawing set 1, left. The invention is a metal awning for window openings, and more particularly to awnings of the louver type.

UNITED STATES PATENT OFFICE

2,568,215

METAL SHUTTER

Lemuel G. Brown, Oklahoma City, Okla.

Application September 6, 1946, Serial No. 695,155

4 Claims. (Cl. 189—62)

1

My invention relates to metal awnings for window openings, and more particularly to awnings of the louver type.

Louver type awnings usually consist substantially of a rectangular frame which surrounds the window opening and is rigidly connected to the outside face of the window frame. Horizontally disposed vertically spaced louvers extend across the frame opening and are pivotally mounted at each end on horizontal axes. The louvers are so spaced vertically that their adjacent horizontal edges over-lap when they are in closed position. Means is provided for pivotally actuating the louvers simultaneously from the inside of the window opening.

The principal object of the present invention is to provide a means for preventing the passage of light between the louver frame and the ends of the louvers, when the louvers are in their closed positions.

Some present day louver-type awnings have inwardly or downwardly turned end wings, which lie perpendicular to the axes of the louvers, and which are provided for the purpose of excluding light rays from traveling across the outside edge of the louver frame and beneath the ends of the louvers, when they are in closed or substantially closed positions. Such wings are efficient in accomplishing the purpose for which they are intended, but they do not stop light rays from passing through the crack lying between the exterior surface of the wings and the adjacent surface of the louver frame.

An object of the present invention is to close this crack, not only against the passage of light rays, but also for the purpose of catching driving rain and directing it downwardly on outside surface of the window frame.

In some metal awnings using wing-type overlapping louvers, as above described, indented pockets are provided in the exterior surfaces of the inside ends of the wings for nesting the outside ends of the wings on the louver next above. The formation of such pockets causes a separate manufacturing operation, and if the louvers ever become slightly bent from their original form, the wings are prone to bind in the pockets and prevent proper closing of the louvers.

It is an object of the present invention to provide a winged louver which requires no pockets for nesting the wing of the adjacent louver, and which at the same time provides space in which the above mentioned crack closing means may operate.

Other objects will be apparent from the following description when taken in conjunction with the accompanying two sheets of drawings, wherein:

- 5 Figure 1 is a perspective view showing the louvers in their fully open positions;
- 10 Figure 2 is a fragmentary perspective view looking at the inside of the louvers which are shown in their fully closed positions;
- 15 Figure 3 is an exploded perspective view showing the separate parts of the assembly and its actuating mechanism, and showing only a fragment of one louver and of the louver connecting drip strip;
- 20 Figure 4 is a horizontal sectional view detailing the relationship of certain parts of the device;
- 25 Figure 5 is a fragmentary perspective view showing the inside surface of the end portion of one louver and its perpendicular end wing; and,
- 30 Figure 6 is a schematic view showing the outside face of one louver, and also depicting its central portion in vertical section.
- 35 Like characters of reference designate like parts in those figures of the drawings in which they occur.
- 40 In the drawings:
- 45 The reference numeral 1 indicates, as a whole, a substantially rectangular sheet metal louver-frame, having vertical side members 2, a horizontal top member 3 rigidly connecting the upper ends of the side members, and a horizontal bottom member 4 rigidly connecting the lower ends of the side members. The top member 3 has an outwardly extending horizontal visor 5 which projects beyond the outside edge portions 6 of the two side members 2. The inside or most inwardly extending portions of the side members 2 are indicated by the reference numeral 7. The portions 7 are actually flat flanges which are adapted to be mounted flatly either against the outside face of a usual window frame, or if a fly-screen is provided over the window opening, the flanges 7 and the top and bottom members are mounted flatly against the outside face of the fly-screen frame. In Figures 2 and 4 the reference numeral 8 indicates a vertical side member or rail of a usual fly-screen.
- 50 Extending horizontally across the louver-frame opening, indicated by the reference numeral 9, there is provided a plurality of identical louvers 10. Each louver is formed of an elongated strip, preferably of sheet metal, slightly arcuate in cross-section (Figure 6), and having a crimped
- 55

bead along its inside edge 11 and a similar bead along its outside edge 12, when the louvers are in open position (Figure 1). When the louvers are in their closed positions (Figure 2), the inside edge 11 becomes the "upper edge" and the edge 12 becomes the "lower edge," as will be more fully described hereinbelow. Therefore, in the present specification and in the appended claims, when referring to an edge of a louver, the words "inside" and "upper" are synonymous, and the words "outside" and "lower" refer to the identical other edge.

The two ends of each louver are not parallel with each other, the inside or upper edge 11 being shorter than the outside or lower edge 12 (Figure 6). Lying substantially at right angles or perpendicular to the longitudinal axis of each louver, and at each end of the louver, there is provided a wing 13. The wings 13 are preferably formed integral with their louver, and project downwardly when the louvers are open (Figure 1) and inwardly when the louvers are closed (Figure 2). The wings 13 preferably extend across the full width of the louver, and intermediate their ends, each wing is provided with a self-formed semi-spherical "wart" or boss 14 which projects from the exterior surface thereof (Figures 4, 5 and 6), and each of which has a central perforation 15.

The outer flanges 6 of the side members 2 are spaced perforated to receive rivet-type pivot pins 16, which pass through the perforations 15 in the wings 13, and which act to pivotally mount the louvers in the frame 1 in position to span the louver-frame opening 9. Surrounding each of the pins 16, the flange 6 is provided with a semi-spherical "wart" or boss 17 which abuts one of the bosses 14 so as to provide a reduced area of frictional contact therewith. The free edge portion of each of the wings 13 is preferably provided with a self-formed reinforcing rib 18.

The pins 16 are so spaced vertically in the flanges 6, that when the louvers 10 are pivotally turned to their closed positions as shown in Figure 2, the lower edge 12 of one louver overlaps the upper edge 11 of the next louver sub-jacent thereto.

The fact that the upper edge 11 of one louver is slightly shorter than the lower edge 12 of the louver next above, makes it possible for the upper edge 11 of the lower louver to pass between the lower ends of the wings 13 on the next louver thereabove, when the louvers are being rotated into their closed positions. This eliminates the necessity for any pockets in the wings.

As a means for selectively rotating or swingably pivoting the louvers 10 simultaneously, the following described mechanism is provided.

Referring more particularly to Figures 2 and 3, the left hand edge portion of the fly screen rail 8 is embraced by the adjacent faces of two plates 20 and 21 which together form a bracket 22. The plate 20 contacts the inside face of the rail 8, and is held rigidly in place by screws 23. To the left hand edge of the rail 8 is attached by a screw 24 the lower end of a brace or bearing bracket number 25 having a loop 26 at its upper end. The plate 21 is positioned along the outside face of the screen rail 8, and the two plates are alignedly perforated as shown at 27 so that they, and the loop 26, may receive the horizontal shank portion 28 of a rotatable actuating handle or crank 29. As illustrated in the drawings, the loop 26 may be selectively tightened around the shank portion 28 of the handle 29. A bolt 50 is provided for this purpose. The end portion of the shank is pro-

vided with threads 30, and adjacent thereto its sides are flattened as indicated by the numeral 31. The flattened portion 31 is adapted to be inserted snugly within a straight sided slot 32 in one end of an arm 33. A lock-washer 34 and nut 35 are installed upon the threaded end of the shank 28 to hold the handle and its associated parts in assembled relation whereby the shank and arm may be selectively rotated by operation of the handle.

As a means for opening and closing the louvers simultaneously by selective movement of the handle 29, each wing 13 of all of the louvers 10 have their upper inside corner portions through perforated as indicated at 36. A combination drip-rail and actuating bar 37, formed of angle iron, has one of its flanges 38 extending vertically along the exterior surfaces of said wings 13, and its other flange 39 envelops the inside edges of the wings 13. Surrounding each of the perforations 36 the wings are provided with self-formed "warts" 40. The flange 38 of the actuating bar 37 is provided with vertically spaced through perforations 41 and these perforations, and the perforations 36, each complementally receive a pivot pin 42. The arrangement is such that vertical reciprocation of the bar 37 causes pivotal movement of the louvers. One of the bars 37 is provided along both ends of the louvers, and therefore, should one of the bars be moved vertically, the other one also moves simultaneously.

The bars 37 are each so located with relation to the adjacent flange 6 of the side member 2, that it bridges the crack between the flange 6 and the wings 13. This crack is caused by the above described provision of the two bearing bumps or "warts" 14 and 17, and also by the fact that the ends of the louvers are not parallel. Although the flange 38 of the bar 37 is also provided with a bearing bump for contacting each of the "warts" 40 of the wings 13, the flange 39 of the bar lies behind the crack thus formed, and bridges the same to exclude light rays, and to prevent ingress of driving rain. The outside face of the flange 39 catches such rain and causes it to gravitate downwardly to drip upon the upper surface of the outwardly and downwardly sloping portion 43 of the bottom member 4 of the louver frame 1.

As a means for selectively reciprocating one of the bars 37 vertically to actuate the louvers 10, the flange 39 is provided with a through perforation 44 (Figure 3), and a pivot pin 45 acts to pivotally connect the upper end of a link 46 to said flange. The lower end of the link 46 is pivotally connected by a pivot pin 47 to the swinging end of the arm 33. The handle 29, shank portion 28, and the arm 33 act as a crank for operating the link 46 and bar 37.

The pivotal connection between the arm 33 and the link 46 is so arranged that when the louvers are closed, the pivot pin 47 lies slightly beyond dead center, so that the louvers are effectively locked in their closed positions. The free end of the bracket plate 21 has an outwardly turned flange 48 which acts as a stop for the swinging end of the arm 33.

As stated hereinabove, the bars 37 act as means for causing simultaneous movement of the louvers, and for effectively closing the vertical cracks between the side members 2 and wings 13, and also provide drip rails for moisture. Also; that by tapering or bevelling the ends of the louvers, no pockets are required in the wings 13 in order that they may nest with each other. It is therefore believed that structure has been dis-

closed which will accomplish all of the objects and purposes for which it is intended.

Obviously the invention is susceptible to some change or alteration without defeating its practicability, and I therefore do not wish to be confined to the preferred embodiment shown in the drawings and described herein, further than I am limited by the scope of the appended claims.

I claim:

1. In shutter construction, the combination with a rigid frame having a central opening with vertical side members; a plurality of vertically spaced substantially straight horizontal louvers extending across said opening between said side members, of: a substantially straight wing at each end of each louver extending laterally thereof, and lying in a plane substantially perpendicular to the face thereof, the wings of each louver converging toward one louver edge; and means pivotally mounting the wings on similar ends of said louvers to a frame side member in such relation that the wings of one louver overlap those of the next adjacent louver, when the louvers are in closed positions.

2. In shutter construction, the combination with a rigid frame having a central opening with vertical side members; a plurality of vertically spaced horizontal louvers extending across said opening between said side members, of: a substantially straight wing at each end of each louver extending laterally thereof, and lying in a plane substantially perpendicular to the face thereof, the wings of each louver converging toward one louver edge; means pivotally mounting the wings on similar ends of said louvers to a frame side member in such relation that the wings of one louver overlap those of the next adjacent louver, and in such relation that spaces occur between the side members and the wings; and a vertical L-shaped strip pivotally connected to the similar wings of said louvers for causing their simultaneous pivotal movement in the frame, one flange of said strip disposed to lie in

said spaces, and the other flange bridging said spaces laterally when the louvers are in closed positions.

3. In shutter construction, wherein a substantially rectangular frame opening is spanned by a plurality of vertically spaced horizontally disposed louvers, said louvers being pivotally mounted in the frame on horizontal axes, so that the outer horizontal edges thereof may be swung downwardly into overlapping relation with the inner edges of the next subjacent louver: a substantially straight wing at each end of each louver and lying substantially perpendicular to the louver face, the two wings of each louver converging toward one longitudinal edge thereof.

4. In shutter construction, wherein a substantially rectangular frame opening is spanned by a plurality of vertically spaced horizontally disposed louvers, said louvers being pivotally mounted in the frame on horizontal axes, so that the outer horizontal edges thereof may be swung downwardly into overlapping relation with the inner edges of the next subjacent louver, a louver construction including: a strip having a trapezoidal face; a straight wing extending across each end of said strip, and lying substantially perpendicular to said face.

LEMUAL G. BROWN.
